UNITED STATES PATENT OFFICE

1,996,773

MINING APPARATUS

Charles F. Osgood, Claremont, N. H., assignor to
Sullivan Machinery Company, a corporation of
Massachusetts

Application December 30, 1932, Serial No. 649,584

29 Claims. (Cl. 262—28)

This invention relates to mining apparatus, and more particularly to improvements in coal mining apparatus of the wheel mounted, track supported and guided, kerf cutting type.

5 An object of this invention is to provide an improved mining apparatus. Another object is to provide an improved coal mining apparatus of the wheel mounted, track supported and guided, kerf cutting type. A further object is to provide 10 in a mining apparatus of the above character, an improved power operated adjusting mechanism for the kerf cutting mechanism. Still another object is to provide a mining apparatus of the type wherein the kerf cutting mechanism is mounted on a tiltable support and having associated therewith improved power operated support tilting means. Still another object is to provide 15 in a mining apparatus of the above character, an improved turntable mounting for the tiltable support, the support tilting means having embodied therein improved turntable rotation means. These and other objects and advantages of the invention will, however, hereinafter more fully appear.

20 In the accompanying drawings there is shown for purposes of illustration one form which the invention may assume in practice.

In these drawings,—

25 Fig. 1 is a plan view of the illustrative embodiment of the improved mining apparatus.

Fig. 2 is a side elevational view of the mining apparatus shown in Fig. 1.

30 Fig. 3 is an enlarged fragmentary side elevational view with parts shown in section, illustrating the improved support tilting and turntable rotating mechanism.

Fig. 4 is an enlarged, central, longitudinally extending, vertical sectional view taken substantially on line 4—4 of Fig. 1.

35 Fig. 5 is a horizontal sectional view taken substantially on line 5—5 of Fig. 4.

Fig. 6 is a detail vertical sectional view taken on line 6—6 of Fig. 3.

40 Fig. 7 is a detail horizontal sectional view taken on line 7—7 of Fig. 3.

In this illustrative embodiment of the invention there is shown a coal mining apparatus of the wheel mounted, track supported and guided, kerf cutting type generally comprising a portable base herein a truck 1 mounted on wheels 2 and supported and guided by a mine trackway 3. Mounted on the truck 1 is a horizontal turntable 4 swiveled about a vertical axis and in turn having pivotally mounted thereon at 5, for tilting movement relative thereto about a transverse

axis, a support 6. Mounted on the forward end of this tiltable support 6 is the kerf cutting mechanism generally designated 7. Interposed between the rearward portion of the turntable and the rearward end of the tiltable support 6 is the improved support tilting and turntable rotating mechanism, generally designated 8. Mounted on the rearward portion of the truck is the truck propelling mechanism generally designated 9.

The turntable structure comprises an upstanding annular flange 10 formed integral with the truck 1, and the turntable 4 is provided with a depending flange 11 mounted on a suitable bearing 12 supported by the flange 10. A series of rollers 13 are provided for reducing the friction between the rotating and stationary parts of the turntable, while mounted concentrically with the bearing 12 is a central turntable bearing 14. The turntable 4 overlies the truck wheel axes, and is mounted on the truck for rotation about a vertical axis lying intermediate the truck wheel axes. Formed integral with the turntable are upstanding brackets 15 having bearing caps 16 which receive trunnions 17 projecting laterally from the sides of the support 6 adjacent the forward end of the latter. Mounted on the forward end of the tiltable support 6 in advance of the trunnion 17 is a cutter carrying head 18 having depending vertical guideways 19 extending downwardly in advance of the forward end of the truck. 30 Mounted for vertical movement along the guideways 19 are guides 20 secured to a cutter support 21, in turn having pivotally mounted thereon for swinging movement about a vertical axis relative thereto a horizontal kerf cutter 22. This 35 kerf cutting mechanism is substantially identical to that disclosed in the patent to one Morris P. Holmes, Patent No. 1,819,778, granted August 18, 1931, except, in this instance, the cutter head is a rigid head and the kerf cutter may be positioned 40 relative to the head to cut a horizontal kerf at the level of the mine bottom outside and below the level of the mine trackway. If desired, the cutter head may be a "turnover" or rotating head as disclosed in the patent. This cutting mechanism specifically comprises a horizontal motor 25 mounted on the rearward portion of the tiltable support 6 and having its power shaft 26 extending longitudinally of the support. Keyed to the forward end of the motor power shaft 26, as shown 45 in Fig. 4, is a bevel pinion 27 meshing with a bevel gear 28 which drives, through a telescopic torque shaft 29, a cutter driving sprocket 30 journaled within the cutter support 21 and engaging and driving a cutter chain 31 mounted for circula-

tion about the margin of the bar 32 of the kerf cutter. A screw and nut mechanism 33 is provided controlled by a clutch mechanism 34 for adjusting the cutter support 21 in a vertical direction along the guideways of the cutter head. Keyed to the torque shaft 29 is a gear 35 which drives, through spur gears 36 and 37, a clutch controlled slow speed gear train 38 and a clutch controlled high speed gear train 39, and these gear trains are selectively operable to drive through worm gearing 40, a spur pinion 41 meshing with an internal gear 42 secured to the kerf cutter thereby to effect swinging movement of the kerf cutter about its pivot. As the specific driving mechanism for the cutter and the specific cutter adjusting and swinging mechanisms are clearly described in the above mentioned Holmes patent, and do not specifically enter into this invention, further description thereof is deemed unnecessary.

The truck propelling mechanism 9 comprises a motor 45 which drives, through suitable reduction gearing, and plural speed gearing housed within a casing 46 and controlled by a hand wheel 47, a chain sprocket 48. This chain sprocket is connected through a chain and sprocket connection 49 with the rear truck wheel axle. The truck propelling mechanism therefore affords means for driving the truck wheels to propel the apparatus along the trackway at cutting and transport speeds. As the specific construction of this truck propelling mechanism does not enter into this invention, further description thereof is considered unnecessary.

Now referring to the improved support tilting and turntable rotating mechanism 8, it will be noted that journaled on the rearward extremity of the motor power shaft 26 is a spur pinion 50 connectible to the motor shaft by a suitable clutch mechanism 51. As shown, a jaw clutch is provided, but if desired a friction clutch may be used. This spur pinion meshes with a large spur gear 52 suitably journaled within bearings 53 carried within the rearward portion of the support 6, as shown in Fig. 7. Arranged centrally within the spur gear 52 and splined therein for axial sliding movement relative thereto is a shaft 54 connected through a universal joint 55 to a relatively inclined shaft 56, in turn connected through a universal joint 57 to a longitudinal shaft 58. If desired the gear 52 may be connected in driving relation with the shaft 58 through a flexible transmission shaft or other similar transmission means. The shaft 58 is suitably journaled within bearings carried within a casing 59 mounted at the rear end of the cutter support 6, for tilting movement about a transverse axis parallel with the axis of tilting movement of the support 6 and having lateral trunnions 60 arranged within bearing bracket 61 extending rearwardly from the rearward end of the tiltable cutter support 6. Keyed to the shaft 58 is a worm 62 meshing with a worm wheel 63 enclosed within the tiltable casing 59. This worm wheel is secured by screws 64 to a sleeve 65 having formed at its lower end a nut 66 engaging the threads of a screw 67. Arranged centrally within the sleeve 65 is a sleeve 68 splined at 69 to the screw shaft 67. The outer sleeve 65 is provided with a clutch element 70 connectible by a sliding clutch element 71 to a clutch element 72 formed on a sleeve keyed at 73 to the inner sleeve 68. A non-rotatable clutch element 74 is rigidly secured to the upper portion of the casing. If desired rotation of the element 74 might be controlled by a suitable

frictional holding device which would yield when the screw and nut mechanism reaches its limit of adjustment. In this instance, the lower end of the screw shaft 67 is connected through a universal joint 75 to a vertical shaft 76 suitably journaled within a casing 77 formed integral with the turntable 4. Keyed to the lower end of the shaft 76 is a spur gear 78 meshing with the teeth of a gear segment 79 formed on the vertical flange 10 of the turntable bearing structure. 10 The sleeve 68 and the screw threaded shaft 67 cooperate to form a telescopic torque shaft through which the gear 78 is driven from the motor 25 to effect rotation of the turntable 4 about its axis irrespective of the tilted position 15 of the cutter support 6 relative to the turntable. The elements of the telescopic torque shaft also cooperate to form a screw and nut adjusting mechanism to effect tilting of the cutter support 6 relative to the turntable. If it is desired to 20 effect rotation of the turntable, the clutch element 71 is slid downwardly to connect the clutch elements 72 and 70 together, thereby connecting the sleeves 65 and 68 together for simultaneous rotation, and due to the splined connection between the sleeve 68 and the screw shaft 67 the elements rotate as a unit, thereby to effect drive of the turntable rotating pinion 78. The connection of the pinion 50 with the motor shaft is controlled by the clutch 51. If it is desired to 25 effect tilting of the cutter support 6 relative to the turntable, the clutch element 71 is slid upwardly to connect the clutch element 72 with the non-rotatable clutch element 74, thereby to effect holding of the sleeve 68, and upon rotation of the 30 worm wheel 63 and nut 66, the latter travels upwardly or downwardly along the screw 67 to effect tilting of the support. During tilting movement of the support, the gear casing 59 rocks about its trunnion mounting relative to the support, while the splined connection of the shaft 54 with the gear 52 and the universal joints 55 and 57 permit constant drive between the gear 52 and the shaft 58 during such tilting movement. The universal joint 75 compensates for any tilting movement of the screw 67 out of alignment with the shaft 76. It will thus be seen that the motor 25 carried by the tiltable support 6 not only effects drive and adjustment of the kerf cutter, 35 but also effects tilting of the cutter support and rotation of the turntable.

As a result of this invention, it will be noted that an improved mining apparatus is provided having improved power operated tilting and rotating mechanism for the tiltable cutter support 55 and turntable mounting structure for the cutting mechanism. It will further be noted that an improved mechanism is provided wherein the cutter support and turntable mounting structure are tilted and rotated in an improved manner by 40 a common means and by motor operation. These and other advantages of the improved mining apparatus will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a mining apparatus, a portable base, a 75

- support mounted on said base for tilting movement relative thereto about a transverse axis, a kerf cutter on said tiltable support, a motor on said support for actuating said kerf cutter, and devices driven by said motor and arranged at the rear end of said support for tilting said support relative to said base and including extensible, universally mounted adjusting devices between said support and base. 5
- 10 2. In a mining apparatus, a portable base, a turntable mounted on said base for rotation about a vertical axis, a support mounted on said turntable for tilting movement relative thereto about a transverse axis, a kerf cutter mounted on said tiltable support, and common motor operated devices for rotating said turntable and for tilting said support relative to said turntable and including extensible, universally mounted adjusting devices between said support and turntable. 15
- 15 3. In a mining apparatus, a portable base, a turntable mounted on said base for rotation about a vertical axis, a support mounted on said turntable for tilting movement relative thereto about a transverse axis, a kerf cutter mounted on said tiltable support, and common motor operated devices for rotating said turntable and for tilting said support relative to said turntable having a driving motor carried by said tiltable support. 20
- 20 4. In a mining apparatus, a portable base, a turntable mounted on said base for rotation about a vertical axis, a support mounted on said turntable for tilting movement relative thereto about a transverse axis, a kerf cutter mounted on said tiltable support, and common motor operated devices for rotating said turntable and for tilting said support relative to said turntable having a driving motor carried by said tiltable support and by which motor said kerf cutter is also driven. 25
- 25 5. In a mining apparatus, a portable base, a turntable mounted on said base for rotation about a vertical axis, a support mounted on said turntable for tilting movement relative thereto about a transverse axis, a kerf cutter mounted on said tiltable support, a motor carried by said tiltable support for actuating said kerf cutter, and devices actuated by said motor for tilting said support relative to said turntable. 30
- 30 6. In a mining apparatus, a portable base, a turntable mounted on said base for rotation about a vertical axis, a support mounted on said turntable for tilting movement relative thereto about a transverse axis, a kerf cutter mounted on said tiltable support, a motor carried by said tiltable support, and devices actuated by said motor for tilting said support relative to said turntable and for rotating said turntable relative to said base. 35
- 35 7. In a mining apparatus, a portable base, a turntable mounted on said base for rotation about a vertical axis, a support mounted on said turntable for tilting movement relative thereto about a transverse axis, a kerf cutter mounted on said tiltable support, a motor carried by said tiltable support, and devices actuated by said motor for rotating said turntable and including a frame mounted on said tiltable support, a driving element journaled on said frame, and telescopic driving elements adjustably mounted between said driving element and turntable. 40
- 40 8. In a mining apparatus, a portable base, a turntable mounted on said base for rotation about a vertical axis, a support mounted on said turntable for tilting movement relative thereto about a transverse axis, a kerf cutter mounted on said tiltable support, a motor on said support for actuating said kerf cutter, and devices driven by 45
- 45 said motor and arranged between the normally rearward portion of said turntable and the normally rearward end of said tiltable support for tilting said support relative to said turntable and including extensible adjusting and supporting means arranged between said support and turntable for tilting said support and for holding said support in its different tilted positions. 50
- 50 9. In a mining apparatus, a portable base, a turntable mounted on said base for rotation about a vertical axis, a support mounted on said turntable for tilting movement relative thereto about a transverse axis, a kerf cutter mounted on said tiltable support, a motor on said support for actuating said kerf cutter, and devices driven by said motor and arranged between the normally rearward portion of said turntable and the normally rearward end of said tiltable support for tilting said support relative to said turntable and for rotating said turntable. 55
- 55 10. In a mining apparatus, a portable base, a turntable mounted on said base for rotation about a vertical axis, a support mounted on said turntable for tilting movement relative thereto about a transverse axis, a kerf cutter mounted on said tiltable support, and motor operated devices between the normally rearward portion of said turntable and the normally rearward end of said tiltable support for rotating said turntable and including a telescopic torque shaft, a driven element journaled on the turntable, and a universal joint connecting an element of said torque shaft with said driven element. 60
- 60 11. In a mining apparatus, a portable base, a turntable mounted on said base for rotation about a vertical axis, a support mounted on said turntable for tilting movement relative thereto about a transverse axis, a kerf cutter mounted on said tiltable support, motor operated devices between the normally rearward portion of said turntable and the normally rearward end of said support for rotating said turntable and tilting said support relative to said turntable including a bracket on the normally rearward end of said support, an element swiveled on said bracket, and adjustable devices between said swiveled element and the normally rearward portion of the turntable and including elements through which said turntable is rotated and said support is tilted. 65
- 65 12. In a mining apparatus, a portable base, a turntable mounted on said base for rotation about a vertical axis, a support mounted on said turntable for tilting movement relative thereto about a transverse axis, a kerf cutter mounted on said tiltable support, and motor operated devices between the normally rearward portion of the turntable and the normally rearward end of said tiltable support for rotating said turntable and tilting said support relative to said turntable including motor operated screw and nut mechanism and driving means therefor carried by said tiltable support, said screw and nut mechanism including an element through which said turntable is rotated and said support is tilted. 70
- 70 13. In a mining apparatus, a portable base, a turntable mounted on said base for rotation about a vertical axis, a support mounted on said turntable for tilting movement relative thereto about a transverse axis, a kerf cutter mounted on said tiltable support, and motor operated devices for rotating said turntable and for tilting said support including a motor carried by said tiltable support, and adjustable turntable rotating and support tilting connections driven by said motor and arranged between the normally rearward 75

portion of the turntable and the normally rearward end of said support.

14. In a mining apparatus, a portable base, a turntable mounted on said base for rotation about a vertical axis, a support mounted on said turntable for tilting movement relative thereto about a transverse axis, a kerf cutter mounted on said tiltable support, motor operated devices for rotating said turntable including a motor carried by said tiltable support, adjustable driving connections driven by said motor and arranged between the normally rearward portion of the turntable and the normally rearward end of said support including brackets on the normally rearward end of said support, an element swiveled on a horizontal axis on said brackets, and adjustable connections between said swiveled element and the normally rearward portion of the turntable.
15. In a mining apparatus, a portable base, a support mounted on said base for tilting movement relative thereto about a transverse axis, a kerf cutter carried by said support, a motor on said tiltable support for actuating said kerf cutter, and devices driven by said motor for tilting said support about its pivot relative to said base, said devices including extensible adjusting and supporting means extending between the rear end of said support and said base for tilting said support and for holding said support in its different tilted positions.

16. In a mining apparatus, a portable base, a cutter support mounted on said base for horizontal swinging and vertical tilting movements relative thereto, a kerf cutter on said support, a motor on said support, and devices driven by said motor for horizontally swinging and vertically tilting said cutter support and including telescopic driving elements adjustably mounted between said support and base.

17. In a mining apparatus, a portable base, a cutter support mounted on said base for horizontal swinging and vertical tilting movements relative thereto, a kerf cutter on said support, a motor on said support, and devices driven by said motor for horizontally swinging and vertically tilting said cutter support, said devices operative to effect tilting and swinging of said cutter support irrespective of the position thereof relative to said base and including a telescopic torque shaft adjustably mounted between said support and base.

18. In a mining apparatus, a portable base, a support mounted on said base for tilting movement relative thereto about a transverse axis, a kerf cutter carried by said support, a motor on said tiltable support for actuating said kerf cutter, and devices driven by said motor for tilting said support about its pivot relative to said base and including extensible, adjustably mounted tilting devices extending between the rear end of said support and said base.

19. In a mining apparatus, a portable base, a cutter support mounted on said base for horizontal swinging and vertical tilting movements relative thereto, a kerf cutter on said support, a motor on said support for actuating said kerf cutter, and devices driven by said motor for horizontally swinging and vertically tilting said cutter support and including telescopic driving and adjusting elements adjustably mounted between said support and base.

20. In a mining apparatus, a portable base, a cutter support mounted on said base for horizontal swinging and vertical tilting movements relat-

tive thereto, a kerf cutter on said support, a motor on said support for actuating said kerf cutter, and devices driven by said motor for horizontally swinging and vertically tilting said cutter support, said devices operative to effect tilting and swinging of said cutter support irrespective of the position thereof relative to said base and including extensible adjusting and supporting means extending between said support and base for tilting said support and for holding said support in its different tilted positions.

21. In a mining apparatus, a portable base, a turntable mounted on said base for rotation about a vertical axis, a support mounted on said turntable for tilting movement relative thereto about a transverse axis, a kerf cutter mounted on said tiltable support, and motor operated devices for rotating said turntable and for tilting said support relative to said turntable including common turntable rotating and support tilting devices extending between said support and turntable.

22. In a mining apparatus, a portable base, a turntable mounted on said base for rotation about a vertical axis, a support mounted on said turntable for tilting movement relative thereto about a transverse axis, a kerf cutter mounted on said tiltable support, motor operated devices for rotating said turntable and for tilting said support relative to said turntable including common turntable rotating and support tilting devices extending between said support and turntable, and a motor carried by said tiltable support for actuating said aforesaid common rotating and tilting devices.

23. In a mining apparatus, a portable base, a turntable mounted on said base for rotation about a vertical axis, a support mounted on said turntable for tilting movement relative thereto about a transverse axis, a kerf cutter mounted on said tiltable support, motor operated devices for rotating said turntable and for tilting said support relative to said turntable including common turntable rotating and support tilting devices extending between said support and turntable, and a motor carried by said tiltable support for actuating said aforesaid common rotating and tilting devices and by which said kerf cutter is also driven.

24. In a mining apparatus, a portable base, a turntable mounted on said base for rotation about a vertical axis, a support mounted on said turntable for tilting movement relative thereto about a transverse axis, a kerf cutter mounted on said tiltable support, a motor carried by said tiltable support, and devices actuated by said motor for tilting said support relative to said turntable and for rotating said turntable relative to said base including common support tilting and turntable rotating devices adjustably mounted between said support and turntable.

25. In a mining apparatus, a portable base, a turntable mounted on said base for rotation about a vertical axis, a support mounted on said turntable for tilting movement relative thereto about a transverse axis, a kerf cutter mounted on said tiltable support, and motor operated devices between the normally rearward portion of said turntable and the normally rearward end of said tiltable support for tilting said support relative to said turntable and for rotating said turntable and including common support tilting and turntable rotating devices adjustably mounted between said support and turntable.

26. In a mining apparatus, a portable base, a cutter support mounted on said base for horizon-

- tal swinging and vertical tilting movements relative thereto, a kerf cutter on said support, a motor on said support, and devices driven by said motor for horizontally swinging and vertically tilting said cutter support and including common support swinging and tilting devices adjustably mounted between said support and base.
27. In a mining apparatus, a portable base, a cutter support mounted on said base for horizontal swinging and vertical tilting movements relative thereto, a kerf cutter on said support, a motor on said support, and devices driven by said motor for horizontally swinging and vertically tilting said cutter support and including common support swinging and tilting devices adjustably mounted between said support and base, said devices operative to effect tilting and swinging of said cutter support irrespective of the position thereof relative to said base.
28. In a mining apparatus, a portable base, a support mounted on said base for tilting movement relative thereto about a transverse axis located near the front end of said base, a kerf cutter on said tiltable support, a motor mounted on said tiltable support to the rear of said transverse axis and by which said kerf cutter is actuated, and devices driven by said motor and arranged between the rear end of said support and said base for tilting said support relative to said base.
29. In a mining apparatus, a portable base, a support mounted on said base for horizontal swinging movement relative thereto and for tilting movement relative thereto about a transverse axis normally located near the front end of said base, a kerf cutter on said tiltable support, a motor mounted on said tiltable support to the rear of said transverse axis when the support is in normal transport position, and by which motor said kerf cutter is actuated, and devices driven by said motor and extending between the normally rear end of said support and said base for tilting and horizontally swinging said support relative to said base.

CHARLES F. OSGOOD.
